GOLF CLUB

William L. Wetzlaufer, Buffalo, N. Y.

Application January 13, 1934, Serial No. 706,511

7 Claims. (Cl. 273—77)

This invention relates to improvements in golf clubs and more particularly to clubs of the "driver" type, i. e. drivers, brassies and spoons.

The standard models of such clubs are designed on the assumption of par play and give substantially maximum results as used by expert or highly competent players whose stance, "swing" and "timing", due to natural or acquired ability, are perfect or nearly so. Such standard models, however, vary from one another in respect to club head weight, weight distribution, the slant or pitch of the face of the club head, and in sundry other respects, these variations being in recognition of the fact that different individuals will have different personal requirements in accordance with their variations in physique and stature. The selection of a proper club is, therefore, a matter of importance and requires care and sound judgment.

Unfortunately even with the best available selection the ingrained faults of a large percentage of players militate against effective results, that is to say the player cannot adapt himself to the club and the club cannot be adapted to the incurable playing idiosyncrasies of the individual or to his particular physical characteristics. A number of factors contribute to this lack of adaptability. The difficulty most frequently encountered is that of club head weight, that is to say the club head is in many cases of relatively too great weight or has its weight unsuitably distributed and the timing and control of the swing, particularly where there is lack of strength or too great flexibility in the wrists, is seriously impaired.

Research has shown that club head weight is not the dominant or controlling factor in the length of the drive. It has been established that the length of the drive may actually be increased by the use of a club head of less than standard weight. The assumed advantage of the heavier club head is its contribution to proper playing form, i. e. control of the club head during the swing, timing of the swing, perfection of the arc, and the "follow through".

The invention has generally for its objects a golf club of the driver type in which a lighter club head may be used to obtain the advantage of longer drives for the average player and which may readily be adapted to the personal requirements of any individual.

A further object is to provide such a club which may, as occasion requires, due to peculiarities of the terrain or of the particular "hole" being played, be adapted for an intentional hook or

slice, notwithstanding that the club is essentially intended and available for the correction of the common faults of hooking and slicing.

A further object is to provide a club having the features described and which is readily convertible as to type, that is to say, available for use on the one hand strictly as a driver or, on the other hand, as a brassie or spoon.

An embodiment of the invention is illustrated in the accompanying drawing, wherein:

Figure 1 is a perspective view of the club head.

Figure 2 is a central vertical section of the club head taken through the driving face.

Figure 3 is a horizontal section of the club head.

Figure 4 is a perspective view of the club head parts detached and arranged in the relation of their assembly.

In the construction preferred the club head body 1 is of generally standard or normal outline and outside dimensions but has a relatively large opening 2 between its top and bottom faces. This opening conforms in contour to the outer face of the club head and materially lessens the weight. The club head body 1 may be composed of any suitable material, the only requirements being that the material shall have the requisite strength and shall be of suitable weight. Excellent results have been obtained with club heads composed of an aluminum alloy, various compositions of which are well known on the open market under different trade names. An aluminum alloy club head of the form shown and having the opening 2 is of less weight than a standard club head of substantially the same dimensions and is of even greater strength due to the "skin" along the wall of the opening 2 and along the outer face of the club head body as a result of the casting operation.

The adaptability of the club head to the requirements of a particular individual involves adjustments of the impact face, the weight and the weight distribution. No set formula for these adjustments can be laid down. Indeed it is from this fact that there arise the deficiencies of the standard club heads in which a determined fixed relation of the factors is assumed as correct. The club head of the present invention is, on the other hand, characterized by a large degree of flexibility or latitude in the adjustments in question and in the relation of these adjustments to one another, the particular adjustments being determined by personal experiment in each case.

The club head body 1 is formed at its front with a flat face 3 which is preferably inclined upward and inward and which provides a bear-

ing or base surface for the companion elements by which the adjustment of the striking or impact face is determined. These elements are an inner plate 4 and an outer plate 5, the outer face 5 of which is the impact face of the club head. The plate 4 rests against the face 3 and the plate 5 rests against the plate 4. These plates are suitably fixed in a determined relation of adjustment, relatively to one another and to the club 10 head body. The means for this purpose preferably consists of a bolt 6 and a wing nut 7. The bolt head fits in a central opening 8 in the plate 5 and is flush with the impact face, the bolt passing through alining openings 9 and 10 in the 15 plate 4 and club head body and the wing nut 7 bearing against the inner face of the club head body as provided by the opening 2. Upon tightening the wing nut the parts are clamped together in the obvious manner. The plates 4 and 5 20 are preferably positively secured against pivotal displacement about the bolt 6. Thus the plate 4 has on its inner and outer face projections 11 which fit in recesses 12 and 13 in the adjacent face of the plate 5 and in the face 3 respectively. 25 One of the companion elements, e. g. the plate 4, is tapered in the direction of its length and the other element, the plate 5, is tapered in the direction of its height. Thus, the element 4 determines the lateral inclination of the impact face 30 and the element 5 determines its vertical inclination. The lateral inclination of the impact face is altered by a reversal of the position of the plate 4 with reference to the bolt 6 as a pivotal center and the vertical inclination is similarly 35 altered by a reversal of the position of the plate 5, the projections 11 and their cooperating recesses 12 and 13 being so located as to be engageable in any of the relative positions of the plates.

40 For the purposes of the adjustment of weight and weight distribution in the club head, provision is made for the application of weights, selectively as to mass and location, to the club head body. In the form illustrated this is effectively and conveniently carried out by a series of threaded recesses 15 in the outer face of the rear wall of the club head body, that is to say the wall at the rear of the opening 2, and by weights 16 in the form of threaded plugs or cylinders which are inserted selectively in the recesses 15 and confined therein by the engagement of the threads. As shown the club head is formed with five recesses 15 and the club equipment will include a suitable number of weights 16 which may be of equal mass 55 or which may include sets of weights of different mass. The weights 16 may be placed as desired in the recesses 15 and any desired number of such weights may be employed, the particular openings in which the weights are fitted and the particular number of weights employed being a matter of experiment in every case inasmuch as the essential object of the arrangement is to adapt the club to the individual, in contrast with the current theory of having the individual endeavor to 60 adapt himself to the club.

65 Obviously there may be cases in which the weights 16 will not be required, the club head body itself happening to be of suitable weight, suitably distributed. The total weight of the 70 club head, i. e. club head body, plates 4 and 5 and weights 16, is preferably less than the weight of a standard club head of corresponding outside dimensions.

75 The factors of the weight of the club head body and the distribution of weight therein and the

factor of the inclination, lateral and vertical, of the impact face are related in the production of the desired resultant flight of the ball. As pointed out, this relationship does not follow any set formula; it is to be determined in each individual case by experiment and it will be apparent that the features of club head construction herein described are such that ample latitude for experiment in respect to the related factors is provided for, whereby the individual player can 10 obtain substantially better results, despite, or perhaps because of, his idiosyncrasies of playing form, than he can obtain where he is limited, as in present practice, to the selection of a club head embodying fixed standards of weight, weight distribution and impact face inclination. 15

In addition to the features of utility above described, the club has the advantage of being instantly convertible as to type. This operation involves the adjustment of the position of the 20 plate 5. It will readily be seen that, when the plate 5 is positioned to provide an impact face of less vertical inclination, the club will serve the purposes of a driver and when the plate 5 is positioned to provide an impact face of greater inclination the club will serve the purposes of a brassie or spoon.

The club is well adapted for play by either men or women, boys or girls. Generally speaking, the only distinction is that, in the case of women, 30 boy or girl players, the total club head weight will be less than in the case of men players. In many instances of women, boy or girl players, no addition of weight will be required, that is to say, all the weights 16 will be removed. 35

The shaft of the club may be of ordinary construction, either steel or wood, but, in any case, should be light. The weight of the club, as a whole, is preferably sensibly less than the weight of a standard club of the same shaft length and 40 outside club head dimensions. The construction is such, however, that the major weight of the club is concentrated in the head.

Having fully described my invention, I claim:

1. In a golf club a club head body provided at 45 its front side with a bearing face, juxtaposed plates, one of which rests against the bearing face and one of which provides the impact face of the club head, one of the plates being tapering in the direction of its length and one of the plates being 50 tapering in the direction of its height, and means for securing said plates to the club head body and providing for reversal, individually, of the positions thereof.

2. In a golf club a club head body provided at 55 its front side with a bearing face, companion elements consisting of inner and outer plates, the inner plate resting against said bearing face and the outer plate resting against the inner plate, the outer face of the outer plate being the impact face 60 of the club head, and means for securing said plates to the club head body and providing for reversal, individually, of the positions thereof, one of the plates being tapering in the direction of its length and one of the plates being tapering in 65 the direction of its height.

3. In a golf club a club head body provided at its front side with a bearing face, juxtaposed plates, one of which rests against the bearing face and one of which provides the impact face of the club 70 head, one of the plates being tapering in the direction of its length and one of the plates being tapering in the direction of its height, and means for securing said plates to the club head body and providing for reversal, individually, of the posi- 75

tions thereof, said means including a centrally located element about which the plates may be turned in effecting their reversal.

4. In a golf club a club head body provided at its front side with a bearing face, juxtaposed plates, one of which rests against the bearing face and one of which provides the impact face of the club head, one of the plates being tapering in the direction of its length and one of the plates being tapering in the direction of its height, said plates and said club head body having alining openings and a bolt having its head fitted in said openings and a nut cooperating with said bolt to clamp the plates against one another and against the club head body, the plates being reversible about said bolt as a pivot.

5. In a golf club a club head body provided at its front side with a bearing face, juxtaposed plates, one of which rests against the bearing face and one of which provides the impact face of the club head, one of the plates being tapering in the direction of its length and one of the plates being tapering in the direction of its height, means for securing said plates to the club head body and providing for reversal, individually, of the positions thereof, and means normally effective for positively holding the plates against displacement in the directions of their planes.

6. In a golf club a club head body provided at its front side with a bearing face, jux-

taposed plates, one of which rests against the bearing face and one of which provides the impact face of the club head, one of the plates being tapering in the direction of its length and one of the plates being tapering in the direction of its height, means for securing said plates to the club head body and providing for reversal, individually, of the positions thereof, said means including a centrally located element about which the plates may be turned in effecting their reversal and elements normally effective for positively preventing the pivotal displacement of said plates about said centrally located element.

7. In a golf club a club head body provided at its front side with a bearing face, juxtaposed plates, one of which rests against the bearing face and one of which provides the impact face of the club head, one of the plates being tapering in the direction of its length and one of the plates being tapering in the direction of its height, means for securing said plates to the club head body and providing for reversal, individually, of the positions thereof, said means including a centrally located element about which the plates may be turned in effecting their reversal, the bearing face and the plates having inter-engaging projections and recesses which are normally effective positively to prevent the pivotal displacement of the plates about said centrally located element.
